CLAIM

The ornamental design for an oven, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a first embodiment of an oven showing our new design;

FIG. 2 is a front view of the first embodiment;

FIG. 3 is a rear view of the first embodiment;

FIG. 4 is a top view of the first embodiment;

FIG. 5 is a bottom view of the first embodiment;

FIG. 6 is a right side view of the first embodiment;

FIG. 7 is a left side view of the first embodiment;

FIG. 8 is a perspective view of a second embodiment of an oven showing our new design;

FIG. 9 is a front view of the second embodiment;

FIG. 10 is a rear view of the second embodiment;

FIG. 11 is a top view of the second embodiment;

FIG. 12 is a bottom view of the second embodiment;

FIG. 13 is a right side view of the second embodiment; and,

FIG. 14 is a left side view of the second embodiment.
